UNITED STATES PATENT OFFICE.

MARK W. MARSDEN, OF PHILADELPHIA, PENNSYLVANIA:

REDUCTION OF PITHY PLANTS.

SPECIFICATION forming part of Letters Patent No. 572,091, dated November 24, 1896.

Application filed March 6, 1896. Serial No. 582,127. (No model.)

To all whom it may concern:

Be it known that I, MARK W. MARSDEN, a citizen of the United States, residing at Philadelphia, in the county of Philadelphia and 5 State of Pennsylvania, have invented certain new and useful Improvements in Reduction of Pithy Plants, of which the following is a specification.

My invention has for its object to separate 10 the pithy and the woody portions or shells of plants and to reduce the separated particles to comminuted condition; and to this end my invention consists in the combination of certain reducing-mills and a separator and other 15 parts and appliances, as fully set forth hereinafter and as illustrated in the accompanying drawing, which represents, in part sectional elevation, a reducing apparatus embodying my improvements.

20 The stalks as they are gathered from the field, with or without the leaves, are first cut to suitable lengths, from one to four inches. They may then be dried or partially dried. The cut sections are then broken or divided, 25 so as to divide or open the shell, that is, that portion which surrounds the pith, and the pith and the shell, so far as they have thus been disconnected, are separated from each other, and the sand, dust, and other foreign 30 matters which were upon the shell are also separated therefrom. It is necessary in many instances to further reduce the size of the particles of the pith and to further operate upon the shell, first, to separate therefrom 35 any portions of the pith not already removed, and then to reduce the pith to the form of a coarse meal. I therefore, after the first separation of the pith and shell, screen the pith through one or more screens, taking out the 40 finer particles, which are in a condition for use, and bring together the larger particles and the separated shell, which together are again broken up and reduced to a finer condition. The pith is separated from the shell, 45 and the latter is then reduced to the form of a meal. Different apparatus may be employed in carrying out these operations. I will now describe that which I have found to be effective.

50 A represents a cutting apparatus, to which the stalks are fed in any suitable manner and which may have revolving or reciprocating

cutters. As shown, there are two revolving rollers with diagonal cutter-blades 6 7, between which the stalks pass and are severed, 55 dropping thence into a hopper B.

If desired, heating-coils 8 may be arranged in or around the hopper, so as to dry or partially dry the contents before they pass to the mill C. 60

The mill C is of any suitable character and, as shown, is an ordinary attrition-mill, receiving the cut material from the hopper through a chute 9.

As the mill is of ordinary character, it will 65 not be necessary to describe the details thereof. In the mill C the shell is broken and the greater portion of the pith is separated therefrom and, together with the broken shell, passes downward through a chute 10 to the 70 air-shaft 12 of a separator D. The air-shaft 12 of the separator communicates at its upper end with an enlarged casing 13, with which communicates a pipe 14, leading to an exhaust-fan E, the diameter of the pipe 14 being about one-half of the diameter of the air-shaft, which is open at the lower end, below 75 which is a cone 15. As a result of this construction the air is drawn upward through the separator and carries with it the material received from the mill C, and when this material reaches the casing 13 of the separator, where the force of the draft is reduced, the heavier particles will tend to fall to the bottom of the casing, which is in the form of an 80 inverted cone, and along which they will slide, passing downward at the sides of and through the shaft 12, while the lighter particles are carried into the exhaust-fan E, from which 85 they are discharged through the pipe 16. 90

The particles of shell falling from the lower end of the shaft 12 are received into a hopper 17, which communicates with the inlet of an exhaust-fan G, by which said particles are discharged into a hopper H. The material 95 from the pipe 16 is received in the center of a revolving screen I, arranged within a casing J, the said screen consisting of two or more cylindrical sieves 18 19, arranged concentrically on a shaft 20, the outer ends being 100 open, and the coarser screen 18 extending beyond the finer one and beyond a partition 21. The screen 19 extends beyond the partition 22, and the lower portion of the casing J be-

ing divided by these partitions forms three chambers x y z . The chamber x communicates through a chute 23 with a dust-bin K, which receives the dust which is driven 5 through the fine screen 19 by the blast from the fan E. The chamber y communicates through a chute 24 with a bin L, which receives the finer particles of pith which pass through the screen 18, but which cannot pass 10 through the screen 19. The larger portions of pith and any particles of shell discharged from the fan E and which cannot pass through the screen 18 are discharged from the end of the latter into the chamber z , and thence pass 15 through a chute 26 to a supplemental attrition-mill C', similar to the mill C, but set to grind finer than the mill C. The finer particles from the mill C' pass through a chute 27 into an inclined tube 28, communicating 20 with the air-shaft 12 above the point where the chute 10 enters the same. The air-pipe 28 is larger at the lower than the upper end, and the current of air which is drawn upward through the pipe 28 by the exhausting of the 25 air in the separator creates a current which is sufficient to carry upward the fine particles of pith discharged from the supplemental mill C', so that they pass to the screens and thence to the bin L, any particles which fail 30 to be sufficiently ground being discharged from the screen 18 and being returned to the mill C'. It thus will be seen that the apparatus is automatic in securing a circle of operations, thereby separating the particles 35 which are sufficiently fine and conducting them to the bin L, but always returning the larger particles to the mill C' until they are properly reduced.

Below the open mouth of the pipe 28 is 40 a hopper 29, communicating with a supplemental exhaust-fan G', from which a pipe 30 leads upward to a hopper M. The hopper 29 receives the particles of shell that have been separated from the pith, and these pass to the 45 hopper M and thence through a chute 31 to a feed-mill N of proper construction, which reduces the shell to the form of a meal of proper fineness, and thence the meal is discharged into the bin T.

50 If it is desired to further dry the material operated upon, this may be done by heating the air which passes upward to the separator D, as, for instance, by means of a heated coil F, heated by a furnace Q, and heating-coils 39 surround the hopper H and casing J.

In order that it may be ascertained whether the separator is working properly, an opening v at one side of the casing 13 is provided with glass, through which the contents of the 60 casing may be observed.

The above-described parts may be arranged and constructed in any suitable manner, the different mills and fans being provided with shafts and pulleys, so as to be driven from counter-shafts or lines of shafting or otherwise. As illustrated, however, the different parts of the apparatus are arranged upon the three floors of a building, so that the material discharged from each of the mills and from the screener may pass downward by gravity. 65 70

Without limiting myself to the precise construction and arrangement of parts shown, I claim as my invention—

1. In an apparatus for the separation of pith from the shells of plants, the combination of a cutting-machine, a hopper, means for heating said hopper and the material in transit, a mill, and a separator communicating with the mill, substantially as described. 75

2. In an apparatus for the separation of pith from the shells of plants, the combination of a mill, a separator communicating at its bottom with the mill, means for directing a heated current of air upward to the separator, and a screener having different chambers and communicating with the top of the separator, substantially as described. 85

3. In an apparatus for the separation of pith from the shells of plants, the combination of a mill, a separator communicating at 90 its bottom with the mill, means for directing a heated current of air upward to the separator, a screener having different chambers and communicating with the top of the separator, a supplemental mill connected to one 95 of the chambers of the screener, connections between said mill and the separator, a hopper in said connections, and an exhaust-fan connected to the hopper, substantially as described. 100

4. In an apparatus for the separation of pith from the shells of plants, the combination of a main and a supplemental mill, a separator connected at its lower end with the main mill and with a hopper, means for directing a current of air upward through the separator, a screener having different chambers and a heating agency and communicating with the upper end of the separator and having one of its chambers connected with the supplemental mill, connections between said mill and the hopper, and a fan in said connections, substantially as described. 105 110

In testimony whereof I have signed my name to this specification in the presence of 115 two subscribing witnesses.

M. W. MARSDEN.
